UNITED STATES PATENT OFFICE.

RUDOLF SKUTSCH, OF BRUNSWICK, GERMANY.

DEVICE FOR DIMINISHING THE ROLLING MOTION OF SHIPS.

No. 874,255.

Specification of Letters Patent.

Patented Dec. 17, 1907.

Application filed March 10, 1906. Serial No. 305,321.

To all whom it may concern:

Be it known that I, RUDOLF SKUTSCH, professor, subject of the Emperor of Germany, residing at Brunswick, Duchy of Brunswick, Empire of Germany, have invented certain new and useful Improvements in Devices for Diminishing the Rolling Motion of Ships, of which the following is a specification.

10 This invention relates to an arrangement for the minimizing of rolling movements of vessels, without the rolling movements being converted into pitching movements and it consists of a plurality of rotating bodies 15 which are suspended in swinging supports adapted to be braked, and which rotate in opposite directions with respect to each other.

It is known that the rolling motion of vessels has been diminished through the medium of one or more rotatable elements mounted in swinging supports adapted to be braked, for example, as set forth in Letters-Patent #769493 of September 6, 1904; but 25 when the rolling motion is diminished the vessel's hull is caused to pitch, that is to say, when the rolling motion is diminished a pitching motion is produced, as has been authenticated, reference being had to *Zeitschrift des Vereines deutacher Ingenieure*, June 25th, 1904, page 983, and also the same publication of date of April 2, 1904, page 478. In view of such conditions it is obvious that the causing of the vessel pitching when diminishing the rolling action of the vessel is 30 very objectionable, and to overcome the producing of the pitching when minimizing the rolling action is the object of this invention, and such object is attained by setting up the 35 rotatable elements in such a manner that they will rotate in pairs in opposite directions with respect to each other, whereby on the one hand, as set forth in Patent 769,493, there are produced couples of forces, which 40 minimize the rolling movement, but on the other hand, the transformation of this rolling movement into a pitching movement is prevented, as the couples of forces, which would produce this pitching movement, obtain op- 45 posite direction of rotation with respect to each other and therefore mutually counteract each other. For, in the moment, where the one rotating body might produce a 50 pitching movement with which the bow of the vessel goes down or dips, the other rotating body has the tendency to produce such a

pitching movement that the stern of the vessel dips and thereby is avoided the transformation of the rolling into a pitching movement.

60 In the drawings is shown by way of example a device in accordance with this invention capable of minimizing the rolling of vessels without producing pitching movement.

Figure 1 is a longitudinal sectional view of a ship's hull showing the arrangement of a minimizing device in accordance with this invention. Fig. 2 is a cross section. Fig. 3 is a plan. Figs. 4, 5 and 6 are, respectively, a longitudinal section, a transverse section 70 and sectional plan showing the arrangement of the braking device with respect to the rotating bodies.

75 In the drawings the rotatable elements are shown as fly-wheels *m*, *m'*. The fly-wheel *m*, as it appears in Fig. 1 is a section on line A—B of Fig. 2 and the fly-wheel *m'*, as shown in Fig. 1 a section on line C—D of Fig. 2. Each fly-wheel is positioned in a suspended frame *n*, which swings around horizontal pivots *o*.

80 Figs. 4 to 6 of the drawings illustrate the braking device in detail for each frame. Referring to the said figures, *a* denotes a disk fastened upon the shaft *o* of the frame *n* and around said disk is arranged a band *b*, the ends of which are fastened in a known way, to a lever *c*, the latter turning on a pin *e* carried by the lever *d*. By shifting the lever *c* in the direction of the arrow by a weight *f* suspended thereby, the band *b* is pressed fast against the disk *a*. The friction generated between the surfaces in contact with each other of the disk and the band renders more difficult the turning of the frame *n* 95 against the body of the ship.

90 The driving apparatus for the fly-wheels is not shown, but it will be understood that the same can be of any suitable construction. As indicated by the arrows in Figs. 1 and 3, the two fly-wheels are to rotate in opposite directions, so that if the fly-wheel *m*, when viewed from above, rotates in the direction of the hands of a clock then the direction of rotation of the fly-wheel *m'* is reversed.

100 With the foregoing construction and arrangement of the parts and owing to the opposite direction of the rotating bodies, the one of them has the tendency to dip the bow of the vessel in the movement, where the other one has the tendency to press down or dip the stern of the vessel, in order that the 105

110

pairs of forces acting through the rotating bodies upon the body of the vessel mutually counteract each other and that the rolling is minimized without the production of a pitching movement.

5 What I claim is—

1. A device for diminishing rolling movements of a vessel without simultaneously producing pitching movement, comprising a 10 pair of rotatable elements mounted in swinging supports adapted to be braked, one of said elements rotating in an opposite direction with respect to the other, means for braking said supports whereby couples of 15 force acting upon the vessel, are provided, those of the couples which attempt to produce a pitching movement counteract each other, thereby preventing pitching movement of the vessel.

2. A device for minimizing the rolling 20 movements of a vessel without simultaneously producing pitching movement, comprising a pair of rotatable elements having the axis thereof capable of being angularly displaced, one of said elements rotating in an 25 opposite direction with respect to the other of said elements, means whereby the axis of each of said elements can be angularly displaced, and braking means for arresting the angular displacement of said elements.

In testimony whereof I have hereunto set my hand in presence of two subscribing witnesses.

RUDOLF SKUTSCH.
